UNITED STATES PATENT OFFICE

JOHN CIOTTA, OF NEW YORK, N. Y.

FUSIBLE ELEMENT FOR ELECTRIC FIXTURE SOCKETS

Application filed April 16, 1929. Serial No. 355,450.

This invention relates to new and useful improvements in fusible elements for electric lines, and aims to provide a simple and inexpensive element that is adapted for disposition within a conventional socket for an electric fixture.

The purpose of my invention is to provide means for eliminating or for employing in addition to the usual inaccessibly located fuse plugs, means for arrangement directly within the sockets of electric lines for breaking the circuit to the particular socket should the wire to that particular socket become overloaded.

It is well known that usually several outlet sockets are served by one fuse plug, which when blown out will cut off the circuit to all of the said outlets, making it necessary for the burned out plug to be located and renewed, which in all circumstances, is a difficult thing to do. Especially is this a source of annoyance when the fuse boxes are located adjacent the ceilings or in the cellar or basement of the building.

The nature of my particular fusible element is such as to enable it to be disposed within the various outlet sockets within the building, and whenever the particular element within the particular socket becomes burned out, it may be immediately renewed and if an additional fusible element is not at hand, the other lines to the remaining sockets can be employed, which is not now the case in the sole use of the conventional fuse plug boxes, as I have previously stated, usually serve several outlet fixtures.

An important object of this invention is to provide a fusible element that is extremely simple and inexpensive of construction, and that may be merely dropped into the outlet socket after which the bulb, plug or the like may be arranged therein.

In the drawings wherein I have illustrated several embodiments of the invention:

Figure 1 is a view partially in elevation, and partially in longitudinal cross section of a conventional outlet socket within which is arranged one of the fusible elements constructed in accordance with the present invention.

Figure 2 is a detailed longitudinal section through this fusible element.

Figure 3 is a plan view thereof.

Figure 4 is a detailed longitudinal section through a modified type of fusible element.

Figure 5 is a top plan view thereof.

Figure 6 is a detailed longitudinal section through a still further modification of a fusible element, and

Figure 7 is a longitudinal section through yet another embodiment of the present invention.

First having reference to Figures 1, 2 and 3, the fusible element illustrated therein consists of a disk 5 of fiber or other non-conducting material formed centrally with an opening 6. Arranged diagonally through this opening 6 is a strip of fusible material 7 having a weakened point 8 intermediate the ends thereof. The opposite ends of this fusible strip 7 are so bent as to be disposed horizontally within depressions at opposite sides of the disk 5, as clearly illustrated in Figure 2. After the fusible element 7 has been arranged with respect to the disk 5 as illustrated, cover caps 9—9 of suitable metal are arranged upon the opposite faces of the disk, each of the tops as well as the opposite ends of the fusible elements as well as the disk 5 being provided with registering openings, whereby the respective caps and ends of the fusible strip 7 may be secured to the disk, through the medium of screws 10—10.

In order to prevent the caps 9 from rotating, each thereof is formed at its edge at a point spaced from its respective screw 10 with an inwardly extending tongue 11, for engagement within an opening 12 in the disk 5, see Figure 3.

Obviously, the fusible element so constructed may be dropped within the conventional outlet socket A, as illustrated in Figure 1, so that when the bulb, plug or the like is arranged within the socket, the circuit will be completed, through the fusible element as is obvious.

Should the fusible strip 7 burn out under an over-load through the line, the entire fuse

may be removed and a new one inserted in its place.

In the form of the invention illustrated in Figures 4 and 5, the same consists of a disk 5' of fiber or suitable non-conducting material having a central opening or slot 6'. Arranged upon the opposite sides of the said disk at the center thereof are metallic plates 9'-9', each of which is formed at opposed 10 points with inwardly extending tongues 11' for engagement within openings in the disk, so as to prevent the turning of the said plates. These plates are formed centrally with registering openings, and adapted to be passed therethrough and through the slots 6' is a length of fusible metal 7', having a head upon one end and being longitudinally split at its opposite end, so that when this 20 end is passed through the opening in the adjacent plate 9', the sides thereof can be bent laterally as at b-b, to secure the plates and fusible strip in association with the disk 5'.

In the form of the invention illustrated in Figure 6, the device consists of a metallic shell 13, the opposed end of which is of reduced formation and is formed with external screw threads, in order that said lower end may be threaded within a conventional fixture socket. The other end of the shell 25 is provided with internal threads and is of a diameter equivalent to the diameter of the conventional fixture receiving socket, in order that a lamp or the like may be screwed therein, as clearly illustrated. Between the 30 upper and lower ends of this shell the same is formed internally with a shoulder 14 in order to support a fiber disk 15 equipped centrally with a contact button 16 that extends through the disk, and that is provided at its 35 lower end with a spring clip 17.

Removably disposed through an opening in the lower end of this shell 13 is a spring clip 18, said clips 17 and 18 adapted for receiving the opposite ends of a length of fusible metal 19.

In the form of the invention disclosed in Figure 7, the same consists of a fiber disk 19 having a central opening 20 in order to enable a length of fusible metal 21 to be extended therethrough. Arranged upon opposite sides of the disk at the center thereof are metal disks 22-22, formed centrally with openings in order that the opposite ends of the length of fusible metal 21 may 55 be passed therethrough. After being passed through these openings, the ends of the fusible strip are turned laterally and secured to the metal disk by solder as disclosed.

In view of the foregoing description when 60 considered in conjunction with the accompanying drawings, it will be apparent that I have provided several embodiments of a fusible element for electric fixture sockets, each of which is well adapted for all of the 65 purposes heretofore designated, and even

though I have herein shown and described the invention as consisting of certain structural features in each embodiment, it is nevertheless to be understood that some changes may be had therefrom without affecting the spirit and scope of the appended 70 claims.

Having thus described my invention, what I claim as new, and desire to secure by Letters-Patent, is:

1. In a fusible element for electric fixture sockets, a disk of non-conducting material having a centrally disposed opening and a plurality of openings disposed between the central opening and the outer peripheral 80 edge of the disk, said disk adapted for insertion in the fixture socket, metallic plates detachably secured on opposite sides of the disk over the central opening, angular tongues formed integrally on the peripheral 85 edge of each plate and projecting into the second named openings and a fusible metallic strip extending through the central opening and having its opposite ends in contact with the plates, and fastening elements passing through the plates and ends of said fusible metallic strip and into said disk.

2. In a fusible element for electric fixture sockets, a disk of non-conducting material adapted for insertion in the fixture socket 95 and having a centrally disposed opening and being further provided with a groove on each of its sides communicating with the central opening on diametrically opposite sides thereof, said disk being still further provided 100 with threaded bores spaced from the central opening and communicating with the groove, a fusible metallic strip extending diagonally through the central opening and having angular end portions disposed in the groove, 105 metallic plates mounted on the opposite side of the disk over the central opening therein and in contact with the adjacent end of the fusible strip, securing elements extending through the plate and the end portion of the 110 fusible strip and threaded into the bores.

In testimony whereof I affix my signature.
JOHN CIOTTA.
